UNITED STATES PATENT OFFICE.

ARCHIBALD F. REDDIE, OF PHILADELPHIA, PENNSYLVANIA, ASSIGNOR TO
WILLIAM H. McCALLUM AND IRVING McCALLUM.

DESIGN FOR CARPET.

SPECIFICATION forming part of Design No. 24,617, dated August 20, 1895.

Application filed July 12, 1895. Serial No. 555,766. Term of patent 3½ years.

To all whom it may concern:

Be it known that I, ARCHIBALD F. REDDIE, a citizen of the United States, residing at the city of Philadelphia, in the county of Philadelphia and State of Pennsylvania, have invented and produced a new and original Design for Carpet or other Fabric, of which the following, taken in connection with the accompanying drawing, is a specification.

The design illustrated in the accompanying drawing may be wrought or produced in Brussels, Wilton, velvet, or other carpeting and in such colors as may be desired.

In the drawing, *a* is the body, *b* the border, and *a b* the carpet, of which, it may be remarked, there is illustrated one breadth and the portion of another breadth.

The drawing clearly shows the characteristic or distinctive appearance which, when imitated to the carpet or other fabric, constitutes my invention. However, for the sake of fur-

ther description it may be stated that the leading or characteristic features of my design may be said to be the floral ornamentation *c*, spray *d*, and scrolls *e*, displayed upon a background *f*, and in the drawing associated with the marginal bands *g* and *h*.

What I claim as new, and desire to secure by Letters Patent, is—

1. In the design for carpet the body *a*, substantially as shown.
2. In a design for carpet the border *b*, substantially as shown.
3. The design for carpet consisting of the body *a*, and the border *b*, substantially as shown.

In testimony whereof I have hereunto signed my name.

ARCHIBALD F. REDDIE.
